UNITED STATES PATENT OFFICE

WILLIAM F. REACH, OF SPRINGFIELD, MASSACHUSETTS, ASSIGNOR TO A. G. SPALDING & BROS., OF NEW YORK, N. Y., A CORPORATION OF NEW JERSEY

GOLF CLUB AND METHOD OF ASSEMBLING SAME

Application filed July 3, 1928. Serial No. 290,154.

My said invention relates to an improved method of and means for securing metal shafts to golf club heads.

The invention aims to provide a method and means by which such shafts may be secured to the heads to effect a durable and permanent junction without the use of screws or analogous fastening means.

The invention further aims to provide a method and means which will result in a union between the parts in which the swing of the club and impact of club head with the ball will have a tightening rather than a loosening effect.

The invention also aims to provide a connection of this character which will afford a slight amount of resiliency between the club head and shaft thereby compensating for the rigidity of the steel shaft against torsional yield.

The invention also aims to provide a method and means by which the club head and shaft may be secured together in an extremely simple and economical manner.

With these and other objects in view, the invention includes the novel method and means or construction hereinafter described and defined by the appended claim.

What I at present consider the preferred embodiment of said invention is illustrated in the accompanying drawing in which:

Figure 1 is a section through a club head and the lower end of the shaft.

Fig. 2 is a side elevation of the corresponding portion of the shaft before insertion in the bore of the club head, and Fig. 3 is a sectional view of a modification.

Referring by reference characters to this drawing, the numeral 1 designates the club head, here shown as of the wood (driver, brassie or spoon) type, having its hosel portion 1^a provided with a bore 1^b having an internal screw thread which is formed by a helical groove 1^c preferably square in cross section, the bore being preferably tapered as shown, with its smallest diameter at or adjacent the sole of the club.

2 designates the metal shaft which is customarily made of tapered steel tubing.

Upon this shaft, before it is inserted in the

bore of the club head, I permanently secure a sleeve 3 of resilient material.

I prefer to form the sleeve of rubber and to permanently secure it to the shaft by vulcanizing it thereon.

The sleeve is tapered to correspond to the bore and provided with an external screw thread (helical rib 3^a) to fit the thread or helical groove in the bore of the club head. Thereafter, the shaft end is screwed into the bore until the sleeve is firmly wedged therein, and compressed between the shaft and bore of the club head or hosel.

I form the threads in such a direction that the swing of the club and impact of club head on the ball tends to rotate the head in a screw-on direction, and tighten rather than loosen the joint.

The sleeve being resilient gives a slight torsional action which compensates for the objectionable rigidity of the steel shaft.

In the form shown in Fig. 3, the bore of the hosel 1^a is shown as provided with a helical rib 1^c and the sleeve with a helical groove 3^a to receive the rib, being a reversal of the arrangement shown in Figs. 1 and 2.

Having thus described my invention, what I claim is:

A golf club comprising a head having a bore provided with a screw thread and shaft having a resilient rubber sleeve vulcanized thereon having an exterior screw threaded surface engaging the threaded bore.

In testimony whereof, I affix my signature.

WILLIAM F. REACH.
